UNITED STATES PATENT OFFICE.

VERNON C. RANDALL AND JAMES E. McGINLEY, OF PORTSMOUTH, VIRGINIA.

AUXILIARY AIR DEVICE.

Application filed May 22, 1922. Serial No. 562,891.

To all whom it may concern:

Be it known that we, VERNON C. RANDALL and JAMES E. McGINLEY, citizens of the United States, residing at Portsmouth, in

5 the county of Norfolk and State of Virginia, have invented certain new and useful Improvements in Auxiliary Air Devices, of which the following is a specification, reference being had to the accompanying drawings.

10 This invention relates to auxiliary air devices for internal combustion engines, and more particularly to a device of this character which is adapted for connection with 15 the radiator of the engine to draw moistened air therefrom.

15 An important object of the invention is to provide a controlling valve for a device of this character which is simple in construction and arrangement and which does not employ springs, while at the same time 20 graduating the amount of air admitted to the manifold.

25 A further object of the invention is to provide a novel and improved control apparatus for the admission of air to the manifold of internal combustion engines.

These and other objects we accomplish by 30 the construction and arrangement shown in the accompanying drawings wherein for the purpose of illustration is shown a preferred embodiment of our invention and wherein like reference characters designate like parts throughout.

35 In the drawings:

Figure 1 is a side elevation partially in section showing apparatus constructed in accordance with our invention applied to an internal combustion engine;

40 Figure 2 is a detail vertical sectional view taken through the apparatus; and

Figure 3 is a bottom plan view thereof.

Referring now more particularly to the drawings, the numeral 10 indicates a substantially circular cap having a central bore 11 opening through one end thereof, the outer end of the bore being provided with screw-threads 12. The bore 11 communicates with a restricted bore 13 thereby forming 45 interiorly of the cap a shoulder 14 directed toward the open end of the cap. The bore 13 is in communication with a bore 15 formed in an extension 16 and providing an outlet,

the end of the extension being externally screw-threaded, as indicated at 17, for engagement in a screw-threaded opening 55 formed in the wall of the manifold.

The numeral 19 designates a body circular in form and having its exterior screw-threaded, as indicated at 20, for coaction 60 with the screw-threads 12 of the bore 11 of the cap 10. This member is provided with a wrench receiving shank through which opens an inlet 21 communicating with a bore 22 formed in the body 19.

65 The numeral 23 designates an insert of substantially the diameter of the bore 11 of the cap 10 and having its lower end reduced, as indicated at 24, thereby forming a downwardly directed shoulder 25. The insert 23 70 is adapted to be disposed within the cap 10 with its upper end abutting the shoulder 14 of the cap and is held in position by screwing the body 19 into the cap so that the upper end of the body engages beneath the 75 shoulder 25 of the insert, maintaining the same in clamped position between the shoulders.

75 This insert has formed therein bores 80 26 and 27 opening through the upper end thereof and into the restricted bore 13 of the cap. Within these bores are disposed ball valves 28 and 29 which are of different weights and sizes and which normally close ports 30 and 31 connecting the bores 26 and 85 27 with the bore 22 of the body 19 and consequently with the inlet 21. The ports 30 and 31 are normally closed by the valves 28 and 29 and these ports are preferably of different sizes, the port of the bore 26 or 27 90 containing the smaller valve being the smaller. The inlet 21 is in communication through a conduit 32 with the space above the water level in the interior of the radiator 33 by means of which the cooling water of 95

the engine is cooled. This conduit between the inlet 21 and the radiator 33 preferably lies against the exhaust manifold M through substantially the entire length thereof so that moist air drawn from the radiator will 100 be heated by the heat radiating from the manifold. The radiator 33 is provided with an overflow pipe 34, the upper end of which opens into the radiator at a point below the upper end of the conduit 32 so that the water 105 within the radiator will not at any time rise

2
to sufficient height to pass into this conduit.

In the operation of our device, air is drawn by the partial vacuum created within the manifold from the radiator and passes 5 through one of the ports 30 and 31 into the manifold. If the engine be operating at a low speed, only the smaller of the valves 28 and 29 will be open and consequently only a small amount of air will be admitted to the 10 manifold. As the speed increases, the second valve will be lifted from its seat and air will pass through the second port to augment the supply to the manifold.

It will be obvious that while we have dis- 15 closed the use of but two of the valves and ports, the number may be increased to any desired extent and that by so increasing the number of valves and ports employed, the proportion of air admitted to the degree of 20 vacuum formed within the manifold will be more finely regulated it being of course understood that a similar number of graduated valves and ports will be employed in each instance. It will furthermore be obvious that 25 similar changes may be employed without in any manner departing from the spirit of our invention and we accordingly do not limit

ourselves to the specific structure hereinbefore set forth except as hereinafter claimed.

30 We claim:

In an auxiliary air device, a chamber comprising a cap having an outlet adapted for connection with the intake manifold of an internal combustion engine, said cap having a bore provided with a reduction communicating with said outlet, the reduction forming a shoulder, said bore being screw-threaded, a body externally screw-threaded for engagement with the screw-threads of said bore, said body having a bore and an inlet 40 communicating with said bore, an insert fitting the bore of the cap and having a reduction fitting the bore of the body, said insert being provided with a plurality of vertical bores each communicating at its lower end by a port with the bore of the body, and check valves of varying weights disposed within said bores and normally closing said ports.

45 In testimony whereof we hereunto affix 50 our signatures.

VERNON C. RANDALL.
JAMES E. McGINLEY.
